UNITED STATES PATENT OFFICE.

JOSEPH L. FORSYTH AND AMOS BOPP, OF BALTIMORE, MARYLAND.

POWER MECHANISM.

1,396,824.

Specification of Letters Patent. Patented Nov. 15, 1921.

Application filed February 19, 1921. Serial No. 446,445.

To all whom it may concern:

Be it known that we, JOSEPH L. FORSYTH and AMOS BOPP, citizens of the United States, residing at Baltimore, in the State 5 of Maryland, have invented certain new and useful Improvements in Power Mechanism, of which the following is a specification.

This invention relates to improvements in power mechanism, and has for its object to 10 provide a simple and efficient means for increasing the revolutions and consequently the speed of the shaft of the device to be driven.

The invention consists of the novel construction and arrangement of the parts and 15 combination of parts hereinafter more fully set forth in the following specification, and pointed out in detail in the appended claims:

In the accompanying drawing:—

Figure 1 is a side elevation of the invention.

Fig. 2 is a top plan view of one of the rock-arms.

Fig. 3 is a vertical section of Fig. 1 just back of one side of the frame.

Fig. 4 is an end view of the crank-shaft.

Fig. 5 is a detail view of Fig. 1.

Referring to the accompanying drawing, forming part of this specification, 1 designates the sides of the frame which are connected by the webs 2. At one end of the frame is mounted a shaft 3 which is connected with and driven by the motor 4. The said shaft 3 is provided with a series of cam-wheels 5 each having a number of 30 cams 6 projecting therefrom. At the top of the frame 1 and in the center thereof is a shaft 7 on which is mounted a number of rock-arms 8, each of which has one end bent downwardly and both ends of which are 35 bifurcated in the downwardly projecting end of which each of said lock arms 8 is mounted a roller 9 revoluble on the pin 10. The said rollers 9 rest upon and travel over the cams 6 when the device is in operation.

The opposite ends of the rock-arms 8 are 45 each connected by a link 11 to one of the cranks 12 of the crank-shaft 13, the latter being mounted at the opposite end of the frame 1. The said links 11 are pivoted in one end of the rock-arms 8. 50

The shaft 3 is driven by the motor 4 and causes the cam-wheels 5 to revolve. As the cam-wheels 5 revolve with said shaft 3 the cams 6 cause the rock-arms 8 to rock on the shaft 7 and revolve the crank shaft 13. It will thus be seen that each cam 6 causes a complete revolution of the crank-shaft 13 and as there are four cams on each wheel 5 the shaft 13 will be revolved four times to each revolution of the shaft 3, thereby greatly increasing the speed of the crank shaft and consequently the machine or device driven thereby. 60

Having thus described our invention what we claim is:

In a power mechanism, a frame, a shaft mounted on one end of said frame, a series of cam-wheels mounted upon said shaft and each having a number of cams thereon, a shaft mounted in the top of the frame in 70 the center thereof, a number of rock arms mounted on the shaft at the top of said frame and each being bifurcated on both ends and each having one end projecting downwardly, a roller mounted in the downwardly projecting end of each of said rock arms and each impinging against one of said cam-wheels, a crank shaft mounted in the opposite end of said frame and having a number of cranks thereon, and a number of 75 links each being pivoted between the bifurcated end of one of said rock arms and connected at its opposite end to one of said cranks. 80

In testimony whereof we affix our signatures.

JOSEPH L. FORSYTH.
AMOS BOPP.
